(57) **CLAIM**

The ornamental design for a holder for a removable camera screen, as shown and described.

DESCRIPTION

FIG. 1 is a side and rear perspective view of the holder of the present invention, the portions shown in broken lines forming no part of the design sought to be patented;

FIG. 2 is a right side view of the holder of the present invention, the portions shown in broken lines forming no part of the design sought to be patented;

FIG. 3 is a left side view of the holder of the present invention, the portions shown in broken lines forming no part of the design sought to be patented;

FIG. 4 is a rear view of the holder of the present invention, the portions shown in broken lines forming no part of the design sought to be patented;

FIG. 5 is a front view of the holder of the present invention, the portions shown in broken lines forming no part of the design sought to be patented;

FIG. 6 is a top plan view of the holder of the present invention, the portions shown in broken lines forming no part of the design sought to be patented;

FIG. 7 is a bottom plan view of the holder of the present invention, the view partially obstructed, the portions shown in broken lines forming no part of the design sought to be patented; and,

FIG. 8 is a bottom plan view of the holder of the present invention, the view unobstructed, the portions shown in broken lines forming no part of the design sought to be patented.
